UNITED STATES PATENT OFFICE.

ALFRED LINDBERG, OF MOSCOW, RUSSIA, ASSIGNOR TO CORPORATION OF ADLER-WERKE VORM. HEINRICH KLEYER AKTIENGESELLSCHAFT, OF FRANKFORT-ON-THE-MAIN, GERMANY.

TYPE-WRITING MACHINE.

964,924.

Specification of Letters Patent. Patented July 19, 1910.

Application filed February 24, 1909. Serial No. 479,807.

To all whom it may concern:

Be it known that I, ALFRED LINDBERG, merchant, a subject of the German Emperor, and resident of Moscow, in the Empire of

5 Russia, with the post-office address of Mjasnitskaja 36, Haus Eibuschitz, have invented new and useful Improvements in Type-Writing Machines, of which the following is a specification.

10 It is a known practice to divide the type on the type-bars of a typewriting machine into separate groups, the several groups of type belonging to different systems of characters, so that by means of shifting devices 15 the characters of one or other system can be brought into action when the keys are struck.

15 The novel feature of the present invention consists in the platen itself being adapted to be adjusted, relatively to the type, both from group to group and also within each group. The type are mounted in any customary manner, so that the transition from one system of character to another is effected 20 with ease and without any tendency to jam.

25 The subject of the invention is illustrated as a typical example in the accompanying drawing.

Figure 1 is a view of the carriage with 30 the platen; Fig. 2 is a section along the line A—B of Fig. 1; Fig. 3 a section along the line C—D of Fig. 1; Fig. 4 a section along the line E—F of Fig. 1, and Fig. 5 illustrates the shifting of the platen roller in a 35 diagrammatic manner.

40 The roller frame 3, supporting the platen roller 1, direct, is adjustably mounted in a shift frame 2, and is adapted to be fixed in position by means of hooks 9 engaging in holes 45 10, 11 of the frame 2. By means of a spring 12 which presses constantly against a handle 13 or the hook 9 the latter is held in constant engagement with the frame 2. This frame 2 in turn is adjustably mounted in 50 the frame 14, in which it can be adjusted vertically in the usual manner by means of the roller 15 and lever 16. In addition this frame 14 is shifted forward longitudinally in the known manner each time the keys are struck.

55 To prevent jamming between the roller-frame 3 and the shift-frame 2, a parallel guide, consisting of racks 17 and pinions 18 in the usual manner, is interposed so that all

skewing and jamming of the frame 3 is 55 prevented.

The types are arranged on the type-bars (Fig. 5) in two groups 19, 20, each comprising three characters, for example, a capital letter, small letter and a number relating to 60 one language. For instance, the group 19 may be formed of German characters and group 20 of Russian characters.

When it is desired to write anything in 65 German, the roller carrying the paper remains in the position shown in Figs. 1—4. The shifting of the roller within the limits of the group 19 of characters is effected in the usual manner by means of the roller 15 and lever 16, so that large and small letters 70 and numbers can be used alternately. If a Russian word or sentence has to be written, pressure is applied to the handle 13 so that the hooks 9 swing out and the platen and its frame can be pushed downward until 75 the hooks 9 catch in the holes 11 and stop the frame 3 again. The platen now assumes the position II of Fig. 5, so that when the keys are struck the type group 20 comes into 80 operation. The shifting within the limits of this group, for obtaining large or small letters or numbers, is effected in the same way by means of the roller 15 of the lever 16 and the same shift mechanism as in the former case. If German is to be written 85 again, the operation is reversed until the paper roller returns into the position I of Fig. 5.

It will be evident that the shifting operation can be performed without any great 90 trouble and loss of time. Of course, three groups of characters may also be used in place of two; and furthermore, it is not necessary that all the characters in any group should belong exclusively to one language. For example, all the characters of 95 all the groups may belong to the same language, but grouped differently, to facilitate convenience and speed in writing, a far larger number of characters being employed than was hitherto possible.

Now what I claim and desire to secure by Letters Patent is the following:

1. In typewriting machines, the combination with type bars provided with a plurality of groups of characters, of a platen, means for shifting the platen from one group to another and means for shifting the

- platen within the limits of each group, substantially as and for the purpose described.
2. In typewriting machines, the combination with type bars provided with a plurality of groups of characters, of a platen, a shift frame in which the platen is mounted and a carriage frame in which the shift frame is mounted, substantially as and for the purpose described.
- 10 3. In typewriting machines, the combination of type bars provided with a plurality of groups of characters, a platen, a platen frame in which said platen is mounted, a shift frame in which said platen frame is mounted, and a lock mechanism for connecting the shift frame with the platen frame, substantially as and for the purpose described.
- 15 4. In typewriting machines, the combination of type bars provided with a plurality of groups of characters, a platen, a platen frame in which said platen is mounted, a shift frame in which said platen frame is
- 20 mounted, a lock mechanism for connecting the shift frame with the platen frame, and means for operating the shift frame within the limits of each group, substantially as and for the purpose described.
- 25 5. In typewriting machines, the combination with type bars provided with a plurality of groups of characters, of a platen, a special lock mechanism for shifting the platen from one group to another and means for placing the platen under the control of the usual shifting mechanism for shifting it within the limits of each group, substantially as and for the purpose specified.
- 30 In testimony, that I claim the foregoing as my invention, I have signed my name in presence of two witnesses, this sixth day of 35 February 1909.
- 35

ALFRED LINDBERG.
